UNITED STATES PATENT OFFICE

1,998,352

CALIPER AND DIVIDER

Josef Bachmann, Philadelphia, Pa.

Application June 16, 1932, Serial No. 617,660

4 Claims. (Cl. 33—149)

This invention relates to calipers and dividers and the invention will be best understood from a study of the following description, taken in connection with the accompanying drawings 5 wherein:

Figure 1 is a face view of the device.

Figure 2 is a side edge elevational view thereof.

Figure 3 is a sectional view taken substantially on the line 3—3 of Figure 1.

Figure 4 is a perspective view of a slidable block.

Figure 5 is a perspective view of a cross bar with calibrations thereon.

Figure 6 is a perspective view of another slide block.

Figure 7 is a perspective view of the pointer equipped end of one arm of the device.

Figure 8 is a perspective view of a pivot pin to be hereinafter more fully referred to.

Figure 9 is a sectional view taken on line 9—9 of Figure 1.

Figure 10 is a longitudinal sectional view taken substantially on the line 10—10 of Figure 6.

Referring more in detail to the drawings it will be seen that my device as will be made apparent, may be used both as a caliper and as a divider comprises arms 10 and 11 pivoted at one end in any suitable manner and as designated generally at 12.

Each of the arms 10, 11 is formed to provide a pair of parallel portions, the said parallel portions of arm 10 being designated by the reference characters 10a, 10b and the said parallel portions of the arm 11 designated by the reference characters 11a, 11b.

A plate 13 is secured at one end between the free ends of portions 10a, 10b of arm 10 as at 14, and at its free end the plate 13 has formed integrally therewith a pointer 15.

A plate 16 is secured at one end as at 17 between the free ends of the portions 11a, 11b of arm 11 and at its free end plate 16 is provided with an extension 18 equipped with a sleeve or other suitable clamp 19 for securing on said end of the plate 16 a pencil or similar marking element 19.

Slidable on the arm 11 is a substantially rectangular block 20 that is provided with parallel openings 21 for accommodating the portions 11a, 11b of arm 11. A similar block 22 is slidably engaged with arm 10 and has openings 23 extending therethrough for accommodating the portions 10a, 10b of said arm 10. The block 22 may be secured at the desired adjustment on arm 10 through the medium of a set screw 24 as clear-

ly shown in Figure 3, while block 20 may be secured at the desired adjustment by a set screw 20'.

The arm 11, in the present instance, on the part 11a thereof, is provided with a longitudinal scale 25 graduated in terms of inches although the graduations may be in terms of centimeters or other desired units of measurement. In the present instance, the scale is a twenty-five inch scale. The length of the scale will of course depend upon the length of the arm 11. In this connection, it might be stated that the device is especially designed for use by sculptors in the making of statues and with the present device statues ranging from five to twenty-five inches in height may be made as will hereinafter appear.

Block 20 as suggested in Figures 3 and 4 is provided in the edge thereof facing the arm 10 with a recess 32 adapted to accommodate one end of a cross bar 27. The length of the cross bar 27 will depend somewhat on the number of parts into which the sculptor is accustomed to divide the human body. In this connection and as will be clear to those skilled in the art, some sculptors divide the human body into a certain number of parts and in the present instance the device is shown for use by those sculptors which divide the human body into fifty six parts. The bar 27 has one end thereof adapted to fit and pivot within the recess 32 in the block 20 and has the free portion thereof adapted to slide within a slot 26 provided in the block 22 as will be clear from a study of Figures 3 and 6. The bar 27 is provided with an elongated slot which adjacent the end of the bar operating within the slot 32 merges into a substantially circular opening 31 which receives the reduced end 30' of a pivot pin 30, which pin 30 fits in either of the notches 29 provided in the edge of the block 20 through which the recess 32 opens. In this connection, it will be understood that the pin 30 is secured within the selected notch 29 in any suitable manner and that the reduced end 30' of said pin is of a diameter to fit sufficiently snugly within the circular opening 31 to permit pivotal movement of the bar 27, and at the same time prevent sliding movement of said bar relative to the pin.

An index pin 33 somewhat similar to the pin 30 is adapted to fit, and is secured in any suitable manner in either of the notches 29' provided in the edge of the block 22 confronting the block 20 and this pin 33 has a reduced end operating within the aforementioned slot provided in the bar 27 and adapted to be read against the markings on the bar 27. In this connection it will be noted

that for substantially the full length of the slot therein the bar 27 is provided with what may be termed a scale graduated in terms of parts, each graduation line indicating, in the present instance, one-fifty sixth part of the whole, it being recalled that this device is especially adapted for use by sculptors who are accustomed to dividing the human body into fifty six parts.

The block 22 is secured at the desired adjustment on the arm 10 through the medium of a set screw 24 and after final adjustment of the parts the same are secured in proper position by tightening the set screw 24' down on to the bar 27 as suggested in Figure 9.

The manner of using the device by a sculptor and its utility will be apparent from the following: Assuming that a sculptor in making a statue desires that the length of the arm of the statue be equal to thirty three parts of the whole, and the full length of the complete statue is seven inches. The sculptor would first place and secure the block 20 in the position shown in Figure 1 with the end edge thereof facing toward the end of the arm 11 opposite the graduation line 7 of the scale 25. The block 22 on the arm 10 would be moved to a position thereon substantially opposite to the block 20 and secured in position by the set screw 24. The arms 10 and 11 would be spread apart the maximum distance determined by the engagement of the pin 33 in the end of the slot provided in bar 27 at that end of the slot remote from the aperture 31. Next the arm 10 would then be moved inwardly toward the arm 11 until the index pin 33 moves opposite to the thirty-third scale line 23 when the set screw 24' would then be tightened to secure the parts in position.

Upon the making of this final adjustment the distance between the point of the marking instrument 19 and the point 15 will determine the full length of the arm of the statue.

It is thought to be obvious that the length of any other parts of the statue can be readily determined substantially in the same manner.

It will also be apparent that the device can be used as a circle divider and when so used the graduations on the bar 27 would of course be in terms of inches and fractions thereof.

While I have shown only arm 11 calibrated it is apparent that arm 10 may be correspondingly calibrated, and the calibrations both on the arms and bar 27 are such as to give reading in inches although the readings may if desired be in the other units of measurement.

Even though I have herein shown and described the preferred embodiment of the invention it is to be understood that the same is susceptible of further changes, modifications and improvements coming within the scope of the appended claims.

Having thus described my invention, what I claim as new is:

1. In a device of the character described, a pair of arms pivoted at one end, one of said

arms being provided with a scale, blocks slidably engaged with said arms, fastening elements carried by said blocks for securing them at the desired adjustment on said arms, a scale member having an end pivoted to one of said blocks and slidably passing through a slot in the other of said blocks, and an additional fastening device carried by the last named block for engagement with the scale member for securing said arms at the desired adjustment relative to one another.

2. In a device of the character described, a pair of arms pivotally connected together at one end, each of said arms having spaced parallel sides, blocks slidably engaged with said arms and having slots extending therethrough and slidably receiving the sides of said arms, fastening elements carried by the blocks and engageable with the arms for securing the blocks at the desired adjustment, one of said blocks being provided with a laterally opening recess, and the other of said blocks having a third slot extending therethrough, a scale member having an end pivoted within the recess of said one block, and slidably passing through the third slot of said other block, and a fastening element on the last named block engageable with the scale member for securing the arms at the desired adjustment.

3. In a device of the class described, a pair of arms pivotally connected together at one end, blocks slidably engaged with said arms, set screws carried by the blocks and engageable with the arms for securing the blocks at the desired adjustment, pins carried by said blocks, a slotted scale member having pivotal engagement with the pin on one of said blocks and slidably passing through a slot in the other of said blocks, the pin on the last named block engaging the slot in said scale member, and a fastening device carried by the last named block and engageable with the scale member for securing the arms at the desired adjustment.

4. In a device of the character described, a pair of arms pivotally connected together at one end, one of said arms being provided with a longitudinal scale graduated in terms of inches, a slide block on each of said arms, means carried by each slide block and engageable with its arm for securing the block at the desired adjustment, a cross bar pivoted at one end to the block on the scale equipped arm and having a free end portion slidable through a slot on the block of the other arm, said last named block having a device engageable with the cross bar for securing the arms at the desired angular adjustment relative to one another, and said cross bar being provided with a longitudinal scale graduated in terms of parts, and an index carried by the last named block and readable against the graduations on the cross bar as and for the purpose specified.

JOSEF BACHMANN.
